UNITED STATES PATENT OFFICE.

JOHN MILTON JESTER, OF WASHINGTON, DISTRICT OF COLUMBIA.

DESIGN FOR A BOTTLE.

Application filed April 1, 1926. Serial No. 17,152. Term of patent 14 years.

To all whom it may concern:

Be it known that I, JOHN MILTON JESTER, a citizen of the United States, residing at Washington, in the District of Columbia, have invented a new, original, and ornamental Design for a Bottle, of which the following is a specification, reference being had to the accompanying drawing, forming part thereof.

Figure 1 is a side elevation of a bottle showing my new design.

Figure 2 is a cross section therethrough on the line 2—2 of Figure 1, and

Figure 3 is a cross section on the line 3—3 of Figure 1.

I claim:

The ornamental design for a bottle, as shown.

JOHN MILTON JESTER.
